UNITED STATES PATENT OFFICE.

CLARENCE ELWOOD KNOWLES, OF SCRANTON, PENNSYLVANIA.

DESIGN FOR A SHOE-POLISHING STANDARD.

48,826.

Specification for Design.

Patented Apr. 4, 1916.

Application filed July 29, 1915. Serial No. 42,669. Term of patent 14 years.

To all whom it may concern:

Be it known that I, CLARENCE ELWOOD KNOWLES, a citizen of the United States, residing at Scranton, in the county of Lackawanna and State of Pennsylvania, have invented a new, original, and ornamental Design for a Shoe-Polishing Standard, of which the following is a specification, reference being had to the accompanying drawings, forming part thereof.

Figure 1 is a perspective view of the shoe polishing standard, showing my design; and Fig. 2 is a side elevation thereof.

I claim:

The ornamental design for a shoe polishing standard, as shown.

CLARENCE ELWOOD KNOWLES.

Witnesses:

WORTH O. SMITH,
A. M. BLACKMORE.
